CHILTON M. MARSHALL, OF OAKDALE, LOUISIANA, ASSIGNOR OF ONE-HALF TO R. E. POWELL, OF ELTON, LOUISIANA.

SUCKER-ROD ELEVATOR.

1,414,519.

Specification of Letters Patent.

Patented May 2, 1922.

Application filed September 2, 1920. Serial No. 407,725.

To all whom it may concern:

Be it known that I, CHILTON M. MARSHALL, a citizen of the United States, residing at Oakdale, in the parish of Allen and State of Louisiana, have invented certain new and useful Improvements in a Sucker-Rod Elevator, of which the following is a specification.

This invention relates to new and useful improvements in a sucker-rod elevator.

One object of the invention is to provide an elevator of the character described which has been specially constructed for the purpose of lowering sucker-rods into wells and withdrawing them therefrom. As is well known to those familiar with the art of drilling and pumping wells, a sucker-rod is employed for operating the pump down in the well. This rod is made up of a number of joints which are threaded together. In pulling the rod from the well the joints are successively unscrewed and set aside until the entire rod is withdrawn, and in making up the sucker-rod to let it down into the well the joints are screwed together, one at a time as the rod descends. During these operations the rod may be suspended in the bore by means of the elevator herein described which constitutes a much more simple, safe and efficient means than methods now employed for this purpose. The construction of the joints of sucker-rods is also well known, but it may be here explained that the abutting ends of the joints are enlarged, forming heads, one of which is formed with a reduced outwardly threaded nipple which screws into an internally threaded socket in the adjacent end of the adjoining joint, and the elevator is clamped around the joint underneath the head at the upper end thereof and thereby holds the string suspended.

Another object of the invention is to provide an elevator of the character described which is light and simple in construction and which may be easily manipulated to disengage it from the joint and apply it to the next succeeding joint above, when the rod is being lowered, or to the next succeeding joint below when the rod is being elevated.

With the above and other objects in view the invention has particular relation to certain novel features of construction, operation and arrangement of parts, an example of which is given in this specification and

illustrated in the accompanying drawings, 55 wherein:

Figure 1 is a side elevation of the elevator.

Figure 2 shows a plan view of the engaging jaw employed, showing in fragmentary section the fork to which said jaw is attached.

Figure 3 shows a side view of a sliding collar employed, and

Figure 4 shows a side elevation of the actuating lever.

Referring now more particularly to the drawings wherein like numerals of reference designate similar parts in each of the figures, the numeral 1 refers to the shank of the supporting fork whose lower end branches into the spaced prongs 2, 2. The lower ends of these prongs have bearings 3, 3, and between them is located the U-shaped jaw 4. Formed integrally with this jaw are the opposing spindles 5 and 6 which are rotatable in the respective bearings 3 and which support the jaw in the forks. The spindle 6 is somewhat longer than the spindle 5, providing a space between one side of the jaw 4 and the corresponding prong 2, and slidably mounted on this elongated spindle there is a collar 7 which has a peripheral groove 8. The side of this collar, adjacent the jaw 4, has a laterally extending pin 9 which works through a bearing 10 in the adjacent side of the jaw. 80 Pivoted to the corresponding prong 2 there is a manual lever 11. The lower end of this lever is bifurcated forming the fingers 12, 12 which fit into the groove 8 and there is a flat spring 13 which is secured at one end to the shank 1 and its other end presses against the upper end of the lever 11 and thus normally holds the pin 9 projected through its bearing. The upper end of the shank 1 has a 85 swivel connection to the link 14, and the entire elevator is suspended by means of a suitable C-hook 15 which is connected to the link 14. This C-hook has a ring 16 to which the lower end of the cable of a block-and-tackle may be attached. This block-and-tackle is in common use and its operation is well known, but it may be here stated that it is suspended from the top of the derrick and through it the elevator may be raised and lowered.

In operation the upper end of the lever 11 is grasped by hand and forced toward the shank 1 and this will operate to move the

collar 7 in the opposite direction and withdraw the pin 9. The jaw is then slipped over the joint of the sucker-rod underneath the enlarged head at the upper end thereof 5 and the lever 11 is then released which will operate to project the pin across the jaw 4 in front of the sucker-rod to prevent the disengagement of the jaw therefrom. When it is desired to release the elevator the lever 11 10 is again manipulated as above explained and the elevator may then be readily disengaged from said rod.

What I claim is:—

1. An elevator including a suspending 15 fork, formed with prongs at one end, a link having a swivelling connection with the other end of the fork, an arcuate jaw secured between said prongs, one arm of which has a bearing, a lock pin slidable through said bearing, a lever secured to one arm of said 20 fork normally holding the pin projected across said jaw to lock the same in engagement with a rod, said lever being manually

operable to withdraw the pin to permit the disengagement of the jaw from said rod. 25

2. An elevator including a suspending fork, formed with prongs at one end, a link having a swivelling connection with the other end of the fork, an arcuate jaw secured between the free ends of said prongs, 30 one arm of which has a bearing, a collar slidable thereon, a lock pin slidable through said bearing, a lever normally holding the pin projected across said jaw to lock the same in engagement with a rod, said lever being 35 manually operable to withdraw the pin to permit the disengagement of the jaw from said rod, and a suspending means attached to said link.

In testimony whereof I have signed my name to this specification in the presence of two subscribing witnesses.

CHILTON M. MARSHALL.
